(57) **CLAIM**

We claim the new, original and ornamental design of a vape pen or portion thereof, as shown and described.

DESCRIPTION

FIG. 1 is a first perspective view of the vape pen showing our new design;

FIG. 2 is a second perspective view thereof;

FIG. 3 is a first-side view thereof;

FIG. 4 is a second-side view thereof;

FIG. 5 is a third-side view thereof;

FIG. 6 is a fourth-side view thereof;

FIG. 7 is a top-view thereof;

FIG. 8 is a bottom-view thereof;

FIG. 9 is a fifth-side close-up perspective view thereof;

FIG. 10 is a sixth-side close-up perspective view thereof;

FIG. 11 is a seventh-side close-up perspective view thereof; and,

FIG. 12 is an eighth-side close-up perspective view thereof. The broken lines in the in the drawings depict portions of the vape pen that form no part of the claimed design. The vape pen is shown with a symbolic break in its length. The appearance of any portion of the article between the break lines forms no part of the claimed design.

1 Claim, 9 Drawing Sheets
